(57) **CLAIM**

The ornamental design for a fit-for-purpose sensor housing
for a downhole tool, as shown and described.

DESCRIPTION

FIG. 1 is an upper perspective view of the fit-for-purpose
sensor housing for a downhole tool showing my design on
a downhole tool in broken lines.

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof; and,

FIG. 8 is perspective view thereof, a configuration attached
to a downhole tool.

The fit-for-purpose sensor housing for a downhole sensor
tool is a sensor housing to adjust the downhole tool for
purpose of being deployed into a borehole of a particular
diameter and measurement of particular conditions. The
broken line features are illustrative and form no part of the
claimed design.
